Sol Klotz, Brooklyn, N. Y., assignor to Mitchell Brothers Inc., New York, N. Y., a corporation of New York

Application November 7, 1941, Serial No. 104,077

Term of patent 3½ years

To all whom it may concern:

Be it known that I, Sol Klotz, a citizen of the United States, residing at Brooklyn, in the county of Kings and State of New York, have invented a new, original, and ornamental Design for a Nightgown, of which the following is a specification, reference being had to the accompanying drawing, forming part thereof.

In the drawing

Fig. 1 is a front elevational view of a nightgown showing my new design;

Fig. 2 is a rear elevational view thereof.

I claim:

The ornamental design for a nightgown, substantially as shown.

SOL KLOTZ.
